TOOL RECIPROCATOR

Andrew De Vere, Pontiac, Mich., assignor to The
Willis Overland Company, Toledo, Ohio, a cor-
poration of Ohio

Application August 10, 1929. Serial No. 384,932

3 Claims. (Cl. 51—34)

This invention relates to tool reciprocating de-
vices and more particularly to means for axially
reciprocating a grinding wheel.

In grinding operations it is preferable to re-
ciprocate the grinding wheel with respect to the
work. This is especially true in grinding cylin-
drical articles provided with surface grooves or
slots, such as the sleeves of a sleeve valve engine,
in order to avoid the formation of ridges on the
wheel, with consequent inaccuracies in the fin-
ished surface. With this type of work, it is also
necessary that the reciprocating movement be
greater than the width of any grooves in the sur-
face, and that the movement be smooth and con-
stant, without an appreciable stop at the point of
reversal.

Accordingly, the principal object of this inven-
tion is to provide an improved means for recipro-
cating a grinding wheel or other tool to secure
the most desirable movement.

A further object is to construct the reciprocating
device in such a manner that any desired
length of stroke or rate of reciprocation can be
selected for a particular rate of rotation.

25 A further object is to utilize an eccentric or
crank and connecting rod to produce the re-
ciprocating movement, whereby a smooth, posi-
tive reciprocation is obtained with a minimum of
stoppage and frictional loss.

30 These, together with other objects relating to
economies and advantages of construction, will
become more apparent upon consideration of the
particular embodiments of the invention selected
for illustration herein.

35 In the accompanying drawings Figure I is a
schematic plan view of a centerless grinder with
the preferred form of the improved reciprocating
device attached to one end of the grinding wheel
shaft;

40 Figure II is an enlarged section on the line
II—II of Figure I;

Fig. III is a section on the line III—III of
Figure II;

Fig. IV is a plan view of the device shown in
Figs. I, II, and III with the cover plate removed;

Fig. V is a plan view of the eccentric shaft; and
Fig. VI is a sectional view of a modification.

45 Referring to Figures I to V of the drawings,
the numeral 1 represents a conventional center-
less grinder having a grinding wheel 2, mounted
on a shaft or spindle 3 driven by any suitable
means, such as a belt (not shown). A casing
4 is mounted on the frame of the grinder in line
with the end of the shaft 3. The shaft 3 is ex-
tended into the casing and has a worm gear 5

keyed thereon. A pair of supporting rods 6, 6,
are mounted on the rear wall of the casing and
project outwardly therefrom parallel with the
shaft 3, and a frame or cage structure 7 is
slidably mounted upon the rods 6, 6.

60 The upper cross piece 8 of the frame 7 is pro-
vided with a bearing for the shaft 3. Thrust
washers 9 are interposed between the worm gear
5 and the cross piece 8, and between the cross
piece and the nut 10, which is secured to the end
65 of the shaft 3. An eccentric shaft 11 is jour-
nalled in the frame 7 below and at right angles
to shaft 3. Connecting rods 12 are pivoted to the
eccentric portions of the shaft 11 and to rod 13
which is fixed in any suitable manner to the 70
rear wall of the casing 4. A worm wheel 14 is ro-
tatably mounted upon the eccentric shaft 11 in
mesh with the worm gear 5.

75 One side of the worm wheel 14 is provided with
a conical depression 15 for co-operation with a
clutch 16. The clutch 16 is secured to shaft 11 by
means of a key 17, which passes through the clutch
and through a slot 18 in shaft 11. Shaft 11 is
provided with an axial bore 19 extending from one
80 end of the shaft past the slot 18. A spring 20 lo-
cated in the inner end of the bore 19 bears against
the pin 17 and presses the clutch 16 outwardly
to a released position. The outer end of the bore
19 is tapped for co-operation with the threads of
85 a rod 21 which extends inwardly and engages the
outer side of the pin 17. The rod 21 passes through
an aperture 22 in the casing 4 and terminates in
the hand wheel 23. A flexible washer 24 is dis-
posed about the rod 21 and in the aperture 22 to
90 seal the casing but to permit lateral movement
of the rod.

95 When the grinding wheel is rotated the worm
gear 5 drives the worm wheel 14. When the rod
21 has been screwed inwardly to force the clutch
16 into engagement with the conical surface 15
of the worm wheel, the eccentric shaft rotates
100 with the worm wheel 14. The eccentric portions
of the shaft 11 impart motion to the connecting
rods 12 which has vertical and horizontal com-
ponents. The vertical components cause the rods
12 to oscillate about their pivots on the fixed rod
13. The horizontal components force the shaft
11 and the frame 7 to slide horizontally on the
105 supporting rod 6. This motion is transmitted by
the upper cross piece 8 of the frame 7 through the
thrust washers 9 to the shaft 3.

110 When it is desired to dress the grinding wheel,
or to allow the shaft 3 to rotate without recipro-
cating, for any other reason, the rod 21 is screwed

outwardly to allow the spring 20 to force the clutch 16 out of engagement with the surface 15.

In the modified form of the device shown in Fig. VI, the frame is omitted. The eccentric shaft 11 is journalled at the ends in the casing 4. A collar 25 is rotatably mounted on the shaft 3 and bears through thrust washers 9 on the worm gear 5, and through a thrust ball bearing 26 on the nut 10 which is fixed to the end of the shaft. The connecting rods 12 are pivoted to the eccentric portions of the shaft 11 and to studs 27 projecting from opposite sides of the collar 25.

In the operation of this form of the device, rotation of the eccentric shaft imparts a reciprocating motion directly to the shaft 3 through the connecting rods, the collar 25, and the thrust bearings. It will be apparent that since the worm gear 5 is fixed to the shaft 3, the reciprocation of the latter creates an irregularity in the rate 20 of rotation of the wheel 14, and a corresponding irregularity in the rate of reciprocation.

As the eccentric shaft is substantially offset from the axis of the shaft 3, the varying rate of movement of the connecting rod is substantially 25 equal to the varying rate of movement in the reverse direction, thus for equal peripheral movements of points diametrically opposed in a plane transverse to the axis of the eccentric shaft, the alternate reciprocatory movements of the shaft transmitted by means of the connecting rod 12 will be substantially of the same rate of speed 30 variation. The action is very similar to the usual "crank and rod" movement and, while the reciprocatory travel of the shaft is not uniform from one extreme of movement to the other, the action is substantially the same in both directions 35 and has proven very satisfactory.

While I have described in detail two embodiments of the invention, it will be apparent that other modifications can be made, and I do not,

therefore, wish to be limited except as indicated by the following claims.

I claim:

1. In combination with a supporting wall, a primary shaft projecting through said wall, a member projecting from said wall, a cage mounted on said member for sliding movement toward and from said wall, said primary shaft having a thrust bearing in said cage, an eccentric shaft 80 rotatably mounted in said cage and a connecting rod pivoted to said eccentric and to said support, whereby rotation of said shaft imparts a reciprocating movement to said cage and said primary shaft.

2. In combination, a stationary casing; a rotatable drive shaft journalled in said casing; projections on said casing, a cage slidably mounted upon said projections; an operative connection between said cage and said shaft; means within said casing actuated by rotation of said shaft for reciprocating the shaft and cage axially; and means operable from outside said casing for rendering said first mentioned means operative or inoperative at will.

3. In combination with a tool spindle; a movable cage having a portion connected to said spindle; means independent of said spindle for supporting said cage; a shaft journalled on said cage positioned at an angle to said spindle; gearing interposed between said shaft and spindle 100 whereby rotary movement of said spindle causes rotation of said shaft, said shaft having an eccentric; a relatively stationary member spaced from said eccentric; and a connecting rod pivoted to said eccentric and to said stationary member whereby rotation of said shaft imparts movement to said cage for reciprocating said spindle.

CERTIFICATE OF CORRECTION.

Patent No. 1,927,793.

September 19, 1933.

ANDREW De VERE.

It is hereby certified that the name of the assignee in the above numbered patent was erroneously written and printed as "The Willis Overland Company" whereas said name should have been written and printed as The Willys Overland Company as shown by the records of the case in this office; and that the said Letters Patent should be read with this correction therein that the same may conform to the record of the case in the Patent Office.

Signed and sealed this 5th day of December, A. D. 1933.

F. M. Hopkins

(Seal)

Acting Commissioner of Patents.
